SLICING MACHINE AND STRINGER

John Leonard Taylor, Milwaukee, Wis.

Application December 5, 1932, Serial No. 645,674

3 Claims. (Cl. 146—151)

The present invention relates to slicing machines for cutting various articles such as fruit and vegetables, soap, and the like, and an object thereof is to provide improvements generally in the construction and operation of machines of this type.

A further object is to improve the general appearance of such a machine.

A further object is to provide a general arrangement of such a machine in which the working parts are housed and shielded by other necessary parts.

A further object is to provide an improved slicing mechanism.

15 A further object is to provide a new method of determining the thickness of such slicing.

A further object is to provide improved apparatus for effecting such adjustment.

A further object is to provide for slitting or 20 stringing articles sliced in such a machine.

A further object is to provide an improved relation of slicing and slitting cutters in the machine.

A further object is to provide for rendering such slitting cutters inoperative when desired.

25 A further object is to provide novel means for altering the characteristics of the slitting performed by such cutters.

A further object is to provide an improved slitting cutter.

30 A further object is to provide a combination of such cutters which will operate to further the objects above enumerated.

A further object is to provide for ready removal of such cutters from the machine, and for replacement thereof.

35 Further objects are to improve the details of the machine particularly in view of the objects above advanced, and further objects and advantages will become apparent from the following 40 specification and annexed drawings in which:

Figure 1 is a plan view of my improved vegetable slicing machine, as arranged for hand power operation.

Figure 2 is a side elevation of the same.

45 Figure 3 is a plan view of a modified form of the machine, showing an electric motor drive, instead of the hand power drive of Figures 1 and 2.

Figure 4 is an enlarged transverse vertical section drawn on the lines 4—4 of Figures 1 and 5.

50 Figure 5 is an enlarged fragmentary plan view of a portion of the machine shown in Figures 1 and 2, with parts broken away to show details of construction.

55 Figure 6 is an enlarged fragmentary side ele-

vation of a part of the machine shown in Figures 1 and 2.

Figure 7 is a side view of one of a plurality of the vertically arranged slitting cutters, shown with four radial cutting blades.

Figure 8 is a side view of another of the vertical slitting cutters, shown with one radial cutting blade, and indicating in dotted lines a plurality of additional cutting radial blades provided on some of the other cutting members.

Figure 9 is an enlarged transverse section, drawn on the line 9—9 of Figure 7, of one of the radial blades of a cutting member.

Figure 10 is a side view of a spacing washer, one of which is placed between adjacent vertical slitting cutters shown in Figures 7 and 8, and also in Figures 14 to 18 inclusive.

Figure 11 is a central vertical section of the spacing washer shown in Figure 10.

Figure 12 is a detail fragmentary plan view of a portion of the adjustable platform for controlling the thickness of the slices of vegetables cut by the horizontal slicing knife.

Figure 13 is a perspective view of the shaft for carrying the plurality of vertical slitting cutters and spacing washers.

Figures 14 to 18 inclusive are schematic views showing the several adjustable positions, respectively, of the vertical slitting cutters as manually selectively adjusted by the hand-lever pin in register with indicating dial stations on the carriage.

Figure 19 is a fragmentary horizontal section, drawn on the dotted line 19—19 of Figure 4, showing the detail construction of the adjustable guard-plate.

In the drawings, like parts are identified by similar reference numerals throughout the several views.

Referring to the drawings, the device comprises generally in its preferred form, a hopper 20 having an adjustable guard plate 20a, legs or standards 21 supported in anti-skid cushions 21a, a plurality of guide rods 22, 22, and a cross member 23, the several parts connected together constituting the framework of the machine.

A carriage 24, carrying platform 25, particularly shown in Figure 4, and 31, a horizontal slicing knife 26, and vertical slitting cutters 27, reciprocates horizontally immediately below the hopper 20 upon the guide rods 22, 22.

The carriage 24 comprises crossheads 29 and 30 connected together by the horizontal platform 31, through suitable means such as the screws 32. The crossheads 29 and 30 are provided with bear-

ings 33 in the present instance slidably fitted to the guide rods 22, 22.

The crosshead 30 carries the horizontal slicing knife 26 attached thereto in the present instance 5 by screws 35, 35.

The carriage 24 is reciprocated on the guide rods 22, 22 by means of a connecting rod 36 connected at one end to the crosshead 30 through a pin 37 or the like fixed therewith and engaging the 10 rod through a bearing 38, Figure 4, the rod being operatively connected at its opposite end to a crank 39, through the pin 40 fixed with the crank and operative in a bearing 41 in the rod.

The crank 39 may be driven by any suitable 15 means, and conveniently by a hand-crank 42, through the bevel gears 43, 44, as shown in Figures 1 and 2, the latter being carried by a suitable shaft or the like journaled in suitable portions of the cross member 23, and the crank 39 20 being carried by a shaft or other suitable means journaled in the cross member and carrying gear 44.

Or the crank 49 may be driven by any suitable 25 source of power, the means for so driving crank 39 forming no part of the present invention, but for example an electric motor 45, as shown in Figure 3, may drive the crank 39 through a worm 46 meshing with a worm-gear 47, the latter being journaled in the crosshead 23, the motor being 30 connected to the machine in any convenient manner, as by means of screws 48, 48 fitting into a cross member 49 provided therefor on the guide rods 22, 22.

In the crosshead 30, of the carriage 24, is arranged 35 a pair of transversely extending parallel shafts 49 and 50 journaled in bearings 51, 51.

These shafts 49 and 50 support the horizontal 40 platform 25 at various predetermined elevations, as desired by the operator, with respect to the horizontal slicing knife 26, by means of an adjustable lever-arm 52, carried on the shaft 50 45 operating to determine the position of said shafts.

The lever-arm 52 is fixed at one end to the shaft 50 and at its opposite end carries a spring-45 urged pin 53, manually adjustable at various elevations in holes or stations 54 arranged arcuately in the vertical side-panel 55 of the crosshead 30.

Each of the shafts 49 and 50 carries a pair of 50 support members 56, 56, keyed or otherwise fixed therewith, upon which the platform 25 is supported.

The shafts 49 and 50 are operatively connected together, for partial rotation through a pair of meshed gear sectors 57, 57.

To close the space that would otherwise result in all but the uppermost position of platform 25, guard plate 26a is provided, Figures 2, 4, and 19, the plate being slidable up and down in suitable guides 26b, and forming in effect a continuation 60 of a wall of hopper 26. The plate may be moved up and down by suitable means, but in the present instance, for simplicity and convenience is allowed to rest at its lower edge upon platform 25 and follows the adjustments thereof by gravity, 65 thus forming a tight closure between the hopper and platform at all times. Suitable means such as springs not shown may obviously be utilized to insure movement of the guard plate if found necessary within the scope of the invention.

The crosshead 30, of the carriage 24, also carries another transverse shaft 58, journaled in bearings 59, 59. This shaft 58, Figure 13, is preferably non-symmetrical in cross-section intermediate the bearings 59, 59. A plurality of suitably positioned, preferably in the present instance,

vertical slitting cutters 27 and intermediate spacing washers 60 are carried on the non-symmetrical portion of the shaft 58, preferably in present instance to prevent putting slitting cutters on incorrectly, and rotate therewith from one fixed or predetermined position or station to another, as desired by the operator.

Each of the vertical slitting cutters 27 and the spacing washers 60 has a non-symmetrical hole or perforation 28 centrally thereof adapted to fit the 10 similar portion of the shaft 58.

The platform 25 is provided with a plurality of portions 61, 61 at the rear end thereof, each of which are extended between adjacent vertical slitting cutters 27, above the horizontal shaft 58 15 to serve the three fold purpose of guiding and stiffening the thin slitting cutter blades, keeping them wiped free of, for example, sliced vegetable particles, and preventing the radial blades below the platform from slicing the vegetables. 20

Referring to Figures 1 and 4, the platform 25 is loosely pinned to the crosshead 30 by means of a pair of guiding pins 62, 62, rigidly fixed at their top ends to the platform 25 and having a side fit in ports 83 provided therefor in the crosshead 30. 25

The platform 25, being formed of thin sheet metal, is stiffened against bending by means of one or more transverse braces in the present instance illustrated as angle bars 63, Figure 12, spot-welded or otherwise suitably fixed therewith. 30

The plurality of vertical slitting cutters 27, together with the spacing washers 60 and their supporting shaft 58 and adjusting lever-arm 64, are removable as a unit from the carriage 24 of the machine for cleaning purposes, by simply withdrawing the spring cotter pins 65, 65 from their shaft retaining members 66, 66, forming a part of the journal bearings 59, 59.

In the machine shown in full size in Figures 5 40 and 6, the vertical slitting cutters 27 thereof are preferably stamped out from sheet metal of about seven to ten thousandths of an inch in thickness and the cutting knife edges 67 are beveled to a sharp edge 68, Figure 9, in the stamping and 45 forming process, whereby no additional sharpening is required.

The vertical slitting cutters 27, shown in full size in Figures 5 to 8 inclusive, are preferably formed with from one radial cutting blade 69, 50 Figure 8, to four radial blades 70, Figure 7, the radial blades being, in this case, 72 degrees apart, or one-fifth of the circumference of the cutters.

The fifth radial cutting blade is preferably omitted from each of the plurality of cutters 27, 55 so that, on the zero position or station of the adjusting pin 72, Figure 14, in register with the dial 76, none of the vertical slitting cutters are in operative cutting position, and, in this case, horizontal slicing is the only cutting operation of the 60 machine.

In the present machine, the vertical slitting cutters 27, 27 are preferably equally spaced apart one-eighth of an inch, by the intermediate spacing washers 60, 60, affixed upon the supporting 65 shaft 58, although obviously some other spacing would be equally within the scope of the present invention, the portions 61 of plate 25 being spaced accordingly.

Referring to Figure 15, the plurality of vertical 70 slitting cutters 27 are shown positioned at a station designated as $\frac{1}{8}$ ", as is shown by the hand-lever controlling pin 72, which is in register with the dial 76, whereby each vertical slitting cutter 27 has a radial slitting blade 71 substantially ver- 75

tically exposed in slitting position, as indicated above the dotted line 74, 74 in the reciprocating carriage 24, whereby $\frac{1}{8}$ " vertical slicing of the vegetables is effected simultaneously with the horizontal slicing operation.

5 Referring to Figure 16, the plurality of vertical slitting cutters 27 is shown therein positioned at station $\frac{1}{4}$ " as indicated by the hand-lever pin 72 which is in register with the dial 76, whereby each alternate vertical slitting cutter 27 has a radial 10 slitting blade 73, 73 substantially vertically exposed in slitting position, as indicated by that part above dotted line 74, 74, in the reciprocating carriage 24, whereby $\frac{1}{4}$ " vertical slicing of the vegetables is effected simultaneously with the 15 horizontal slicing operation of the machine.

Referring to Figure 17, the plurality of vertical slitting cutters 27 is therein shown positioned at station $\frac{3}{8}$ ", as indicated by the position of the hand-lever pin 72, which is in register 20 thereat with the dial 76, whereby each third vertical slitting cutter 27 only has a radial slitting blade 75, 75 substantially vertically exposed to slitting operation or position, as indicated above the dotted line 74, 74, operative in the reciprocating carriage 24, whereby $\frac{3}{8}$ " vertical slicing of the vegetables is effected simultaneously with the horizontal slicing operation of the machine.

Referring to Figure 18, the plurality of vertical slitting cutters 27 is therein shown as positioned 30 at station $\frac{1}{2}$ ", the adjusting lever-arm pin 72 and dial 76 not being shown in this view, whereby each fourth vertical slitting cutter 27 only has a radial slitting knife-edge 77, 77, as indicated above the dotted line 74, 74 operative in the reciprocating carriage 24, whereby $\frac{1}{2}$ " vertical slicing of the vegetables is effected simultaneously with the horizontal slicing operation of the machine.

40 In operation of the machine, say, for example, it is desired to cut peeled raw potatoes into rectangular shaped bars preparatory to cooking so called "French fried" potatoes, the operation would be as follows:—

45 First, the operator places a few of the peeled raw potatoes at a time into the hopper 20.

Second, the adjustable platform 25 is positioned by the operator, by means of the small adjusting pin 53, of lever-arm 52 in one of the 50 several holes or stations 54 to obtain the desired elevation of the platform 25 with respect to the horizontal slicing knife 26, to cut, for example, $\frac{3}{8}$ " thick horizontal slices from the potatoes, then at the bottom of the hopper, during each 55 forward stroke of the carriage 24.

Third, the vertical slitting cutters 21, 21 are manually adjusted to station $\frac{3}{8}$ ", by turning the shaft 58 manually to the $\frac{3}{8}$ " position shown in Figure 17 by means of the adjusting lever-arm pin 72 registering with the station on dial 76, which provides for $\frac{3}{8}$ " vertical slicing of the potatoes simultaneously with the horizontal $\frac{3}{8}$ " slicing thereof upon each forward stroke of the carriage 24 of the machine.

60 Fourth, the operator continuously turns the hand-crank 42, in the case of the hand-driven machine, or he turns on the current or other power in the case of the power driven machine, whereby the carriage 24 is reciprocated and the horizontal and vertical slicing operations are 65 simultaneously performed.

The sliced potatoes drop from the machine preferably into a pan 82 therefor provided, as fast and as long as the slicing operation takes place.

70 The reciprocating platform 31 is positioned in

the same plane as that of the horizontal slicing knife 26, and it is further located immediately behind the knife and acts as a check plate to control the descent of the unsliced vegetables by retaining them in the hopper 20 upon each forward and each return stroke of the carriage 24, the travel of which is about the length of the hopper. 5

The adjustable reciprocating platform 25 likewise acts as a hopper controlling floor plate in front of the horizontal slicing knife and the vertically adjustable guard plate 20a rides upon platform 25 and assists the rear platform 31 in retaining the charge of unsliced vegetables in the hopper between and during horizontal slicing 15 operations.

The slide bearings 33, of the carriage 24, shown in Figure 4, and all other slide and journal bearings in the machine are preferably fitted with oilless bushings 34 for anti-friction and labor saving purposes, and so that the use of lubricating oil becomes unnecessary. Oil therefore cannot contaminate the vegetables or fruits in process of slicing or cutting.

Referring to Figure 4, the assembly of the adjusting lever-arm 52, which carries the sprung-urged pin 53, is clearly shown therein, and the same comprises a sleeve 78, rigidly connected, as by screw threads, solder or the like at one end thereof, in the free end of the lever-arm 52, and a 30 tubular handle 79 is rotatively mounted concentrically with the supporting sleeve 78, enclosing a coiled expansion spring 80, also concentrically positioned around said sleeve 78. The pin 53 has a turning fit permitting endwise movement of it in the sleeve 78, and has its exterior end affixed to a head end member 81, as by riveting therewith, said member being affixed in the outer end of the tubular handle 79. The spring 80 urges the pin 53 inwardly and retains the latter 40 in one of a plurality of holes or stations 54, arcuately positioned in the side panel 55 of the carriage 24, at various predetermined elevations therein, the platform 25 being thereby adjustable to a level desired by the operator, with respect to 45 the horizontal slicing knife 26.

The hand-lever pin 72 in register with the dial 76 and which controls the width of the vertical slitting or slicing of the vegetables is preferably identically constructed to said lever-arm pin 52 50 previously described.

The machine is preferably constructed largely of polished aluminum, stainless steel or other non-corrosive metals.

The central hopper 20 is preferably cast in- 55 integrally with a top canopy 83 of the machine. The whole being formed to a combined slope of architectural beauty affording ease of cleaning and having relatively great structural strength.

While I have shown my machine in the pre- 60 ferred form, it will be obvious that many changes and modifications may be made in the structure disclosed without departing from the spirit of the invention, the specification and drawings being merely by way of example, and not intended 65 to limit the invention in any manner except as defined in the following claims.

Having described my invention what I claim is:—

1. A slicing machine having a supporting frame, 70 a hopper supported from said frame, a carriage reciprocable on said frame and having a slicing knife and an adjustable platform positioned and guided from said carriage, said carriage having a plurality of shafts journaled therein, gear seg- 75

- ments on said shafts for dependent rotation thereof, said shafts having cranks fixed therewith and supporting said platform, one of said shafts having an indexing arm for selectively determining the position of said shafts and accordingly of said platform and thereby determining slicing thickness, and a vertically slidable guard plate carried by said hopper positioned by and slidable on said platform, and means for reciprocating said carriage.
2. In a slicing machine the combination of an article containing hopper having a discharge opening, a movable retainer plate closing said opening, said hopper being arranged for the progressive movement of articles to be sliced therein toward said movable retainer plate, a knife carried by said plate and positioned to operate during movement of said plate, to slice said articles transversely of their direction of progressive movement, a portion of said plate being adjustable toward and from said knife, means for so adjusting said portion, a shaft having a cross section of an irregular figure and journaled on said plate, a slitting cutter transverse to said knife and comprising a disk segment provided with a cutting edge transverse to the projected circumference of said disk, said disk having a central opening complementary to said shaft whereby it can be placed thereon only in correct angular position.
3. In a slicing machine the combination of an

article containing hopper having a movable wall, and arranged for the progressive movement of articles to be sliced therein toward a movable retainer plate, a knife carried by said plate and positioned to operate during movement of said plate, to slice said articles transversely of their direction of progressive movement a portion of said plate being adjustable toward and from said knife, means for so adjusting said portion, a slitting means comprising a plurality of disk segments, certain segments being provided with single cutting edges and other segments being provided with a plurality of alternatively operable circumferentially spaced cutting edges, said disks being carried on a rod and spaced thereon in predetermined order, the adjustable portion of said movable plate providing a plurality of portions extending between said disk segments, and said cutting edges being so disposed that rotation of said rod will cause predetermined groups of cutting edges to present themselves in cutting position between the extending portions of said plate, other cutting edges being shielded from contact with articles being cut by said adjustable portion of said movable plate, whereby the character of slitting performed may be altered by rotation of said rod into various positions, and means for rotating said rod and locking it in said various positions.

30

JOHN LEONARD TAYLOR.
